UNITED STATES PATENT OFFICE.

OTTO J. GROEHN, OF DETROIT, MICHIGAN, ASSIGNOR TO BRISCOE MANUFACTURING COMPANY, OF DETROIT, MICHIGAN, A CORPORATION OF MICHIGAN.

MULTIPLE-TUBE-FORMING MECHANISM.

1,112,695.

Specification of Letters Patent.

Patented Oct. 6, 1914.

Application filed October 24, 1912. Serial No. 727,532.

To all whom it may concern:

Be it known that I, OTTO J. GROEHN, a citizen of the United States of America, residing at Detroit, in the county of Wayne 5 and State of Michigan, have invented certain new and useful Improvements in Multiple-Tube-Forming Mechanism, of which the following is a specification, reference being had therein to the accompanying 10 drawings.

The invention relates to sheet metal forming machines of that type in which a tubular blank is refashioned to form a multiple unit tube.

15 The invention relates more specifically to the means employed for feeding the blank to the dies and for withdrawing the core member or mandrel from the formed blank, and the invention consists in the construction as hereinafter set forth.

In the drawings: Figure 1 is a plan view of the machine, partly in horizontal section; Fig. 2 is a front elevation.

Generally described the forming machine 25 comprises a core member having a series of fingers or individual cores around which the individual tubes are formed, together with a series of laterally reciprocating die members which successively form the sheet metal 30 about the individual cores. Machines of this type have heretofore been made in which a single multiple unit core member is reciprocated into and out from operative relation with the laterally moving dies, the 35 blank tube being placed upon said core member in advance of its inward movement and being stripped therefrom on its return movement. Such constructions are, however, objectionable; first, for the reason that 40 the engagement of the blank with the core member is a somewhat dangerous operation for the workman; and further because it is difficult to feed the blanks to the machine as fast as it can perform its operations. To 45 avoid these objections as well as to otherwise improve the machine, I have devised a construction of core holder and feeder, in which a plurality of multiple unit cores are successively adjusted into operative relation with 50 the dies and are alternately adjusted to a position where the blank may easily be engaged therewith.

In detail, A is the frame of the machine; B the series of laterally-movable dies; and 55 C a reciprocatory plunger which actuates

cam members D for successively operating said dies.

E is the multiple core member, the individual fingers E' of which are preferably substantially rectangular in cross section, 60 and are loosely connected to a holding member E² so as to be capable of slight relative movement. Instead of employing a single core unit E, I mount a series of said members upon a revoluble head F, which latter is 65 mounted upon a reciprocatory slide member G engaging parallel ways H on the frame. The slide G is reciprocated to insert and withdraw the core member from the dies, and as shown is actuated by a bell crank 70 lever I connected by a link I' with the slide and having its operating arm I² in engagement with a cam J upon the rotary shaft J'. This shaft rotates in timed relation to the operation of the plunger C a 75 sprocket chain R connecting the shaft J' with the driving mechanism (not shown) of the plunger C and the cam J, and is so fashioned as to intermittently rock the bell crank lever to move the slide—the slide remaining 80 stationary in its inward position during the interval of operation of the dies B.

Once during each reciprocation of the slide G the head F is given a partial rotation which will shift one of the core members 85 E out of registration with the dies and will move the succeeding core member in registration therewith. For accomplishing this movement I preferably provide an over-movement of the lever I and connect the 90 same to the slide G through the medium of a resilient, yieldable link. Thus, as shown, the link I' is directly attached to an intermediate slide K engaging bearings upon the main slide G, and a spring L is placed 95 between said intermediate slide and a bearing G' on the main slide.

M is an adjustable stop arranged in the path of the main slide G and adapted to arrest movement thereof before the completion 100 of the movement of the lever I and slide K connected therewith, so that during this continued movement the spring L will be compressed.

N and N' are locking dogs for engaging 105 notches in the rotary head F to hold said head from rotation in either direction. The dog N extends into the path of an actuating pawl O on the slide K, which, during the movement of said slide after the arrest of 110

the main slide G, will trip said dog N and permit of the rotation of the head F in one direction.

P is a laterally-extending arm upon the 5 slide K, which carries at its free end a pawl P' engaging a notched wheel Q upon the rotary head F and timed to actuate said wheel after the withdrawal of the dog N and to turn the same through a sufficient angle to 10 register the next succeeding core member with the dies. Thus during the outward movement of the lever I the slide G will be first moved to its outward limit against the stop M, after which the slide K carrying the 15 arm P will continue its movement and the pawl P' will turn the notched wheel Q, whereby rotary motion will be imparted to the head F for turning one core member out of registration with the dies and another 20 core member in registration therewith.

In operation the attendant places the blank tube upon that one of the core members E which extends outward from the machine and which therefore is accessible and 25 without any element of danger. The blank thus engaged is carried around by the intermittent rotation of the head F until its registration with the dies B, after which during the reciprocation of the head G it is carried 30 inward into operative relation with said dies. Upon the reverse movement of the slide G the formed blank is stripped from the core member by stripping fingers B' on the dies B, and the free core member is 35 carried around by the head F until again in position for engagement with another blank. After each operation the attendant places a blank in engagement with the outwardly-projecting core, so that all of the core members carry blanks as they are successively 40 engaged with the dies.

What I claim as my invention is:

1. The combination with intermittently-operating dies of a core member upon which 45 a blank is placed, insertible into operative relation to said dies, and means timed with the operation of said dies for alternately inserting and withdrawing said core member, and for reversing the same when withdrawn.

2. The combination with opposed, intermittently-operating dies of a series of core members upon which the blanks are placed successively insertible between said dies, and 55 means operating to successively insert and withdraw said core members and to reverse the same when withdrawn for engagement with the blank.

3. The combination with opposed intermittently-operating dies of a core member upon which the blank is placed, a holder to which one end of said core member is attached, means for reciprocating said holder to insert and withdraw said core member in 60 relation to said dies, and means for rotating

1 said holder when withdrawn to reverse the position of said core member for engagement with the blank.

4. The combination with opposed intermittently-operating dies, of a series of core members upon which the blanks are placed, a head to which said core members are secured intermittently rotatable to successively register said core members with the dies, a slide upon which said head is mounted, 75 means operating in timed relation to said dies for reciprocating said head and carrying the registering core member into and out of operative relation with the dies, and means operating upon the outward movement of said slide and complete withdrawal of the core member for partially rotating said head.

5. The combination with opposed intermittently-operating dies of a series of core 85 members upon which the blanks are placed, a rotative head upon which said core members are mounted and from which they laterally project, a slide upon which said head is mounted, means for locking said head successively in position for registering the respective core members with said dies, means timed with the operation of said dies for reciprocating said slide to insert and withdraw the registering core member in operative relation with said dies, and means operating upon the complete withdrawal of said core member for unlocking said head and rotating the same to register another 90 core member with the dies.

6. The combination with intermittently-operating dies of a reciprocatory member operating in timed relation to said dies, a rotary head carried by said reciprocatory member, a series of core members projecting 105 radially from said head and successively registerable with said dies, means for locking said head in each position of registration of a core member with said dies, and means automatically operating upon the outward 110 movement of said reciprocatory member for unlocking said head and rotating the same to a succeeding position for locking.

7. The combination with opposed intermittently operating dies, of a series of core 115 members upon which the blanks are placed, a rotative head upon which said core members are mounted and from which they laterally project, a slide on which said head is mounted, an auxiliary slide having a 120 spring connection with said first-mentioned slide, means connected to said auxiliary slide for normally moving both of said slides to withdraw the registering core member from operative relation with the dies, 125 a stop for the first-mentioned slide, said auxiliary slide being movable after said stop prevents the further movement of the first-mentioned slide against the tension of the spring, and a pawl member adapted to turn 130

the rotative head, operable upon the continued movement of the auxiliary slide to rotate the rotative head to register another core member with said dies.

- 5 8. The combination with intermittently-operating dies, of a series of core members upon which the blanks are placed successively insertible between said dies, and means operating to successively insert and
10 withdraw said core members, said means having a primary and secondary movement in the same direction and adapted on the primary movement to completely withdraw said core members and on the secondary
15 movement to reverse the same.

9. The combination with intermittently-operating dies, of a series of core members

upon which the blanks are placed, intermittently-rotating holder for said core members, successively registering the same 20 with said dies, and means operating when each core member is in registration with said dies for reciprocating the same into and out of operative relation therewith, and means for rotating said holder having its 25 movement controlled by the means for reciprocating the core member.

In testimony whereof I affix my signature in presence of two witnesses.

OTTO J. GROEHN.
